SAFETY LEG FOR ELEVATORS

Louis C. Stukenborg, Memphis, Tenn.

Application August 26, 1931. Serial No. 559,368

9 Claims. (Cl. 254—93)

This invention relates to a leg or support for holding an elevator or lift in raised position until purposely released whereby a safety support is furnished against accidental falling.

- 5 In vehicle lifts of the hydraulic or air actuated type it often happens that a broken connection or other cause allows the lift to drop endangering both life and property. The same thing is true also of elevators not only of the hydraulic type but 10 of that type which are raised by cables in which latter especially safety devices of numerous types are installed to prevent accidental falling because of cable breakage or other failure of apparatus to act.
- 15 The object of the present invention is to provide a safety leg which will automatically follow the raising of an elevator or lift and support same in any position of the device and which must be manually released to permit lowering of the elevator.

20 The means by which the foregoing and other objects are accomplished and the manner of their accomplishment will readily be understood from the following specification on reference to the accompanying drawing, in which:

25 Fig. 1 is a sectional elevation on the center line of the plunger of a hydraulic lift showing the device equipped with duplicate safety legs;

30 Fig. 2 is a perspective view of a rotary automobile lift structure of the free wheel type provided with my improved safety legs; and

35 Fig. 3 is an enlarged fragmentary view showing a check and release valve for the safety leg.

Referring now to the drawing in which the various parts are indicated by numerals, 10 is a vertical cylinder having its top substantially flush with the surface of the ground in which cylinder is a vertically movable plunger 11, to which is secured a circular head 12 on which is rotatably disposed a casting 13, to which rails 14 are secured. 15 is a pipe through which oil or other liquid is supplied to the cylinder 10 from a tank 16 as by means of air supplied through a pipe 17 from a source of supply not shown, and not specifically here set out since the raising means is not inherently a part of the invention. Disposed below the head 12 and secured thereto are one or more of the safety legs which form the subject of the present invention. Each of these legs comprises a vertically disposed hollow cylinder 18 having a closed bottom end in which is disposed a vertically movable hollow plunger 19 which is guided in its movement by guide rings 20, 21, the latter of which preferably forms the bottom of a stuffing box in which suitable packing 22 is held

by a gland 23. The plunger 19 is rigidly secured to the head 12 and is caused to move upward and downward thereby, and therewith. Incidentally in the present construction the leg prevents rotation of the head 12 and the plunger 11 to which it is attached.

Each of the legs is provided with an oil check 24, which check comprises a casing in which a valve 25 is held against a seat by a spring 26. 27 is an opening through the valve casing which allows flow from the plunger to the valve 25. The valve opens automatically to permit transfer of the liquid from the plunger into the cylinder during upward movement of the plunger. The plunger in such event forming a reservoir from

which liquid is supplied to the cylinder to hold the plunger against downward movement. The valve 25 is provided with a stem 28, which extends upward beyond the top of the cylinder and through the head 12 and which may be depressed, 70 as by the rocker arm 29, to move the valve 25 from its seat and allow return flow to the plunger. It will be noted that no stuffing box is provided for the upper end of this stem, thus permitting ingress of air to, and egress from, the reservoir

80 in said plunger and establishing communication between said reservoir and the atmosphere. In the illustrated type in which the casting 13, is rotatable with respect to the head 12 the inner end of the rocker arm 29 rests on a disc 30 from which a centrally disposed pin 31 projects upward through the casting 13 and thereabove is engaged by a lever 32 integral with a rod 33. The rod 33 is provided with a handle 34 accessible to an attendant for the purpose of depressing 85 the stem 28 and valve 25 to permit return flow of the liquid from the cylinder to the plunger.

90 A vehicle lift of this particular type may be provided with one or even more of the safety legs, two, as before stated, being here shown.

95 Ordinarily the size of the plunger is much less than that of the raising plunger with which it is to be associated since leg pressures are static whereas elevator raising plunger pressures are working pressures.

100 In using the device the lift plunger 11 is actuated in usual manner thus raising the head and other appurtenances carried thereby. As the head rises it carries up with it the safety leg plunger or plungers as the case may be causing the liquid within the plunger to flow past the valve 25 to the cylinder 18 thereby at all times keeping the cylinder full of liquid. On cessation of upward movement from any cause whatsoever, the valve 25 automatically seats thereby establishing below

the plunger 19 a closed chamber for the liquid and preventing return movement of the plunger, thus automatically establishing a safety support or leg beneath the elevator table or cage.

5 It will be noted that this leg acts at any and all positions of rise of the lift so that it is only necessary for the support to carry the actual load without provision for impact, since action of the support is coincident with the need thereof. At any 10 time that it is desired to lower the lift the valve may be opened to establish return flow to the plunger and lowering accomplished as though no leg were provided, with the safeguard however that safety action may be invoked on the downward movement at any time by release of the 15 valve controls.

It will readily be understood that a hydraulic elevator may be identically equipped since such elevator is merely a lift of greater range than that here shown.

20 It will also be readily seen that an identical leg may be placed beneath any elevator cage no matter by what means the same may be raised.

It will be readily understood therefore that 25 while the device has been shown as applied to a vehicle lift it is equally applicable to any type of elevator and that in the claims the use of the term elevator specifically covers vehicle lifts as well as other types of elevators.

30 It will also be understood that the liquid supply may be led to the cylinder from other reservoir than the plunger without departing from my invention.

Having described my invention, what I claim 35 is:—

1. In mechanism of the class described, having raising and lowering means, a safety device, comprising a plurality of vertically disposed hollow cylinders, a hollow plunger vertically slid- 40 able within each cylinder, said plunger having a head closing its lower end, and its upper end open to the atmosphere, a supply of liquid in said plungers and cylinders, means on the head permitting flow from the plunger to the cylinder and preventing return flow to the plunger, and manually controlled means for concurrently establishing return flow in all of said cylinders, each plunger extending above its cylinder and being secured to said elevator and movable there- 45 with and thereby, whereby transfer of liquid from said plungers to said cylinders to support said elevator independently of said raising and lowering means, is accomplished by the raising of said elevator, and such support is maintained until said manually controlled means is operated to establish concurrent return flow to a plurality of the plungers.

50 2. In mechanism of the class described, having raising and lowering means, a safety device, comprising a plurality of vertically disposed hollow cylinders, a hollow plunger vertically slid- 55 able within each cylinder, said plunger having a head closing its lower end, and its upper end open to the atmosphere, a supply of liquid in each plunger and cylinder, a valve carried by the head permitting flow from the plunger to the cylinder and preventing return flow to the plunger, and manually controlled means for establishing return flow concurrently in all of said cylinders, each plunger extending above its cylinder and being secured to said elevator, whereby transfer of liquid from said plungers to said cylinders to support said elevator independently of said raising and lowering means, is accomplished 60 by the raising of said elevator, and lowering

thereof may be controlled by said means for establishing return flow.

65 3. In mechanism of the class described, having raising and lowering means, a safety device, comprising a plurality of vertically disposed hollow cylinders, a hollow plunger vertically slid- 70 able within each cylinder, said plunger having a head closing its lower end, and its upper end open to the atmosphere, a supply of liquid in said plungers and cylinders, a valve carried by the head permitting flow from the plunger to the cylinder and preventing return flow to the plunger, and manually controlled means for rendering all of said valves concurrently ineffective, to allow return flow, each plunger extending above its cylinder and being secured to said elevator, whereby transfer of liquid from said plungers to said cylinders to support said elevator independently of said raising and lowering means, is accomplished by the raising of said elevator, and lowering thereof may be regulated 75 by said manually controlled means.

80 4. In mechanism of the class described, having raising and lowering means, a safety device comprising a plurality of vertically disposed hollow cylinders, vertically movable hollow plungers one in each of said cylinders, said plungers extending above said cylinders and being secured to the underside of said elevator and movable thereby and therewith, said plungers each 85 having a head closing its lower end, and its upper end open to the atmosphere, said cylinders and plungers being of length sufficient to allow the full travel of said elevator, supplies of liquid at all times under atmospheric pressure filling 90 each of said cylinders and plungers, check valves one in each of said heads, each permitting flow from a plunger to its cylinder and preventing return flow, and manually controlled means for concurrent opening of all of said valves to allow 95 return flow at the same time from all of said cylinders to their respective plungers, whereby lowering of said elevator when unsupported by said raising and lowering means, is permitted upon concurrent opening of a plurality of said 100 valves.

105 5. In combination with an elevator having raising and lowering means, a safety device comprising a vertically disposed hollow cylinder, a hollow plunger vertically slid- 110 able therein, said plunger extending above said cylinder and being secured to said elevator, and movable therewith and thereby, and having a head closing its lower end, and its upper end open to the atmosphere, a supply of liquid in said plunger and cylinder, a valve carried by said head and normally permitting flow from said plunger to said cylinder while preventing return flow to said plunger, and manually controlled means operable upon said valve for establishing such return flow either when said 115 elevator is in its uppermost position or at any stage of its downward movement, whereby such downward movement may be either checked or permitted to continue at any raised position of the elevator, when it is unsupported by said raising and lowering means, by operation of said valve-control means.

120 6. In combination with an elevator having raising and lowering means, a safety device comprising a vertically disposed hollow cylinder, a hollow plunger vertically slid- 125 able therein, said plunger extending above said cylinder and being secured to said elevator, and movable therewith and thereby, and having a head closing its lower end, and its upper end open to the atmosphere,

- 40 a supply of liquid in said plunger and cylinder, a valve carried by said head and normally permitting flow from said plunger to said cylinder while preventing return flow to said plunger, 80 whereby in the absence of support by said raising and lowering means said elevator is supported by the liquid in said cylinder, and manually controlled means for establishing and regulating return flow to said plunger to permit and control 85 downward movement. 90
- 45 7. The combination with an elevator having raising and lowering means, and manually operable means for the control thereof, of a safety device comprising a vertically-disposed hollow cylinder, a hollow plunger vertically slidable therein, said plunger extending above said cylinder and being secured to said elevator and movable therewith and thereby, said plunger having a head closing its lower end, and its upper end open to the atmosphere, a supply of liquid in said plunger and cylinder, a valve carried by said head and normally permitting flow from said plunger to said cylinder while preventing return flow to said plunger, and manually controlled means independent of said first-named control means, for permitting and regulating such return flow at any stage in the downward movement of said elevator, when said elevator is unsupported by said raising and lowering means, whereby two separate 100 and individually controlled means are provided for holding said elevator against downward movement or regulating such movement. 105
- 50 8. In combination with an elevator having raising and lowering means, a safety device comprising a vertically-disposed hollow cylinder; a plunger vertically slidable therein; a source of 110 liquid supply for said cylinder, said plunger extending above said cylinder and being secured to said elevator, and being movable therewith and thereby, whereby upon upward movement thereof such liquid is drawn into said cylinder by said plunger; a valve normally permitting flow of liquid to said cylinder, while preventing return flow therefrom, whereby in the absence of support by said raising and lowering means, said elevator is supported by the liquid in said cylinder; and manually-operable means for establishing and regulating liquid flow from said cylinder, to permit and control downward movement of said elevator when unsupported by said raising and lowering means. 115
